MAGAZINE FOR FASTENER APPLYING
IMPLEMENTCharles M. Lindstrom, Westerly, R. I., assignor,
by mesne assignments, to Bostitch, Inc., a corporation of Rhode Island

Application November 16, 1946, Serial No. 710,390

7 Claims. (Cl. 1—49)

1

This invention relates to improvements in fastener-applying implements and particularly to hammer-tackers, so-called, adapted to drive double-pointed tacks, staples and similar fasteners for attaching labels, tags and the like to shipping cases, fastening carpets to floors and upholstery to furniture, nailing roofing and siding to buildings, and for many other similar purposes.

One object of the invention is to provide an implement of the type indicated which is simple in construction, economical to manufacture, convenient in use, and especially efficient in performing its intended functions.

Another object of the invention is to provide an implement of the type indicated having a hollow magazine into which a supply of fasteners may be conveniently loaded to rest on the bottom thereof and feed to the applying means.

Another object is to provide an implement of the type indicated having a retractable closure for covering the magazine to hold the staples down therein and operative manually for the dual purpose of withdrawing the fastener-feeding means and opening the magazine to receive a supply of fasteners.

Another object is to provide in a device of the type indicated frictionally-operated means for maintaining the magazine cover in open position with manually-operative means for releasing the frictionally-operated means to permit closing the cover and return of the staple-pushers after the magazine has been loaded with fasteners.

Another object is to provide a device of the type indicated constructed substantially entirely of sheet-metal parts assembled without pins or screws except for a single pivot employed for connecting the operating handle with the magazine-arm of the implement.

Further objects of the invention are set forth in the following specification which describes a preferred form of construction of the implement, by way of example, as illustrated by the accompanying drawings. In the drawings:

Fig. 1 is a side elevation of a fastener-applying implement embodying the improvements of the present invention;

Fig. 2 is a longitudinal sectional view of the implement shown with a portion of its handle broken away and illustrating its operating elements in the same position as in Fig. 1;

Fig. 3 is a longitudinal sectional view of the implement showing its operating elements in position during the operation of driving a fastener into the work;

Fig. 4 is a similar longitudinal sectional view

2

of the implement illustrating the cover of its magazine as withdrawn and the staple-pushers retracted to admit a stick of staples shown as being inserted into the magazine;

Fig. 5 is a plan view of the implement shown with the upper wall of its head as partly broken away to illustrate certain parts therein;

Fig. 6 is a fragmentary sectional view of the implement on line 6—6 of Fig. 1 showing the essential operating elements in its interior;

Fig. 7 is a transverse sectional view of the fore part of the implement taken on line 7—7 of Fig. 5;

Fig. 8 is a transverse sectional view on line 8—8 of Fig. 5 showing the pivotal connection between the parts of the implement and the friction means for holding the magazine-cover in open position; and

Fig. 9 is a perspective view of the staple-pushers.

Fastener-applying implements of the so-called hammer-tacker type are used very generally for attaching tags, labels and the like to articles of commerce and for fastening many other objects in place, such as shingles and siding on buildings, tacking upholstery fabrics to furniture, and fastening carpets to floors. Such hammer-tackers are swung in the manner of an ordinary hammer with the driving mechanism for the fasteners actuated by impact of a movable part of the implement with the work in which the fastener is to be driven. The present invention provides improvements in this type of implement including novel construction of its several elements from sheet-metal formed into shape in dies with a single pivot-screw or bolt connecting the two main parts for relative swinging movement. In addition, the invention provides an improved arrangement of magazine-cover for retaining the fasteners or staples in place therein which is

adapted to be withdrawn to open the magazine and at the same time automatically retract the fastener-feeding means such as a slideable staple-pushers. The magazine then may be conveniently loaded with a supply of fasteners by inserting them through an orifice in the upper handle-member of the device to position them in advance of the feeding means.

Referring to the drawings, Fig. 1 illustrates the implement as comprising a handle-member 2 constructed entirely of sheet-metal shaped into hollow form in suitable dies and comprising a weighted head 3 at its forward end and a finger-grip 4 at the rearward end for securely gripping the handle-member. The finger-grip 4 may be

constructed in tubular form of rubber or other

resilient material adapted to tightly enclose the rearward end of the member 2 in binding engagement therewith and providing a yieldable grip for the hand. Pivoted intermediate the ends of the handle-member 2 within the sides thereof is a magazine-arm 5 for containing the fasteners, also constructed entirely from sheet-metal in hollow form as shown particularly in Figs. 7 and 8. The magazine-arm 5 may be struck up from a strip of sheet-stock folded to provide opposite parallel side walls 6 connected by a bottom wall. The bottom wall is formed by continuous portions of the metal bent into U-shape with upstanding strips 8 connected at the top by a lateral wall 9. In this way the magazine-arm 5 takes the shape of a trough having its side walls 6 spaced apart to abut the sides of U-shaped fasteners or staples S and with longitudinally-extending grooves 10 for receiving the ends of the legs of the staples to adapt them to slide in the magazine while resting on its bottom. As shown in Fig. 5, the inner edges at the top of the side walls 6 of the magazine-arm 5 may be chamfered or beveled slightly at 11 to provide for easy entrance of the staples S into the magazine. The rearward end of the magazine-arm 5 is closed by rectangular wing-portions 12 of the metal folded inwardly from the side walls 6 and meeting at the center as shown in Figs. 6 and 8. At this end of the magazine-arm 5 the side walls 6 are extended upwardly in hinge-ears 13 pierced with holes 14 for receiving a pivot-bolt 15 to hingedly connect the arm to the handle-member 2, see Fig. 8. Preferably, the hinge-ears 13 are punched or swaged outwardly around the holes 14 to form projecting cylindrical flanges 16 providing extended bearing hubs for receiving a cylindrical bushing 20 through which the bolt 15 extends. The bolt 15 is inserted through punched holes 17 in the side walls 21 of the handle-member 2 and a nut 22 on the threaded end of the bolt is set up to bind said walls against the ends of the bushing 20.

At its forward end the metal of the side walls 6 of the magazine-arm 5 is extended upwardly in vertical strips 23 which have rearwardly-extending overhanging portions 24. The side strips 23 have extensions 25 and 26 at their forward ends folded inwardly across the front and disposed in overlapping relationship, as shown most clearly in Fig. 6, to provide an end wall which forms a part of the throat or guideway 27 in which the staple-driver 30 is adapted to reciprocate. Below the extensions 25 and 26, the ends of the side walls 6 of the arm 5 are bent inwardly to provide a pair of projections 28, see Figs. 4 and 6, which serve as abutments to limit the forward feeding movement of the staples S, see Figs. 2 and 6.

To complete the throat or guideway 27 a housing 31 is attached to the forward end of the arm 5 overlying the outer faces of the side strips 23. The housing 31 is formed from a single strip of sheet-metal with a bottom wall 32 and upstanding side walls 33 conforming to the shape of the side strips 23. The side walls 33 of the housing 31 are welded to the side strips 23 and its bottom wall welded to the under side of the arm 5. As shown in Figs. 1 and 2, the under side of the bottom wall 32 of the housing 31 is beveled at 34 to provide an inclined striking face at the end of the arm 5. The sides 33 of the housing 31 are bent or folded inwardly at the front in aligned wings 35 disposed parallel with the forward face of the extension 26 on the side wall 6 of the arm 5 with a space therebetween which forms the

throat or guideway 27 for the staple-driver 30. The inwardly-bent portions or wings 35 of the housing 31 are arranged with their edges spaced apart to provide a vertical slot 36 at the front of the magazine-arm 5. Below the upper edges of the side walls 33 of the housing 31 the metal is slit to form two strips 37, see Fig. 6, which are expanded outwardly to provide projecting detents serving to limit the swinging motion between the handle-member 2 and the magazine-arm 5 in the manner as later explained.

Referring to Fig. 9, the feeding means for the fasteners consists in a staple-pusher 40 constructed from a relatively thin strip of spring-steel having a forward, relatively wide portion 41 adapted to fit between the side walls 6 of the arm 5 and a narrower rearwardly-extending tail-portion 42 terminating in a reversely-bent, upstanding hook 43. The tail 42 of the pusher 40 is received in a pair of slots or recesses 48, see Fig. 8, in the upper edges of the wing portions 12 which form the rear wall of the arm 5. The forward end of the pusher 40 is folded downwardly to provide a vertical wall 44 adapted to engage against the rearmost staple of the series in the magazine 5. At its lower end the vertical wall 44 is folded rearwardly at 45 to provide a seat for the end of a helical spring 46 which extends longitudinally within the sides of the magazine-arm 5 with its rearward end abutting the wing portions 12 which close the end of the arm. The spring 46 is maintained under compression and tends to slide the pusher 40 forwardly to feed the staples S to the driving means at the forward end of the arm 5.

Referring to Figs. 3, 4 and 5, the cover 50 for the top of the magazine-arm 5 is constructed from a strip of sheet-metal folded to provide an upstanding hollow rib 51 extending centrally along substantially the whole length with laterally-projecting side flanges overlying the top of the pusher 40. Adjacent its forward end the metal of the cover 50 is extended laterally in a pair of arms 52, see Fig. 1, which rest on the upper edges of the side walls 6 of the arm 5 with portions folded downwardly to straddle the sides of the arm. The lower ends of the arms 52 are formed at the front with outwardly-projecting finger-rests 53, see Figs. 1 and 7. The rests 53 may be gripped by the fingers for drawing the cover 50 rearwardly to open the top of the magazine in the arm 5 and the rearward end of the cover is adapted to engage in the hook 43 at the end of the tail 42 on the pusher 40 to retract the latter against the tension of the spring 46, see Fig. 4.

The cover 50 is held down against the pusher 40 by resilient means as next described. Coiled around the bushing 20 is a helical spring 55 having one end reaching forwardly in an extension 56, see Fig. 6, bent laterally at its forward end and hooked across the rib 51 on the top of the cover 50. The opposite end of the coiled portion of the spring 55 is anchored at 57 to a rotary latch-member 60 mounted on the bushing 20. As shown more particularly in Figs. 4 and 8, the latch-member 60 is formed of sheet-metal with circular bearing-ears 61 perforated with axial holes for receiving the bushing 20 and connected by an arcuate cross-strip 62. One end of the arcuate portion 62 of the cam-member 60 is extended in a narrow tab or finger-lever 65 which projects upwardly through an opening 66 in the top of the handle-member 2, see Figs. 2 and 8. A larger opening 67 in the top of the handle-

member 2 provides an entrance for inserting the fasteners into the magazine in the arm 5.

Referring to Fig. 2, the lower end of the arcuate cross-strip 62 of the latch-member 60 is normally maintained in engagement with the end of the rib 51 on the cover 50 to hold the cover in its closed position. By pressing the finger against the tab or lever 65 the latch-member 60 may be rocked to release the end of its arcuate cross-strip 62 from the end of the rib 51 to permit the cover 50 to be withdrawn along the arm 5 to open the magazine as shown in Fig. 4. Thereafter, when the latch-member 60 is released the edge of its arcuate cross-strip 62 will engage the top of the rib 51 to apply frictional resistance to the forward movement of the cover 50 whereof to retain it in open position after it has been withdrawn. However, after the magazine in the arm 5 has been supplied with fasteners the latch-member 60 may be released by rocking it in clockwise direction, as viewed in Fig. 4, to allow the cover to be slid forward with the pusher 50 until the forward wall 44 of the pusher engages the rearmost staple S in a stick inserted into the magazine in the arm 5. It is then necessary to manually slide the cover 50 further forward to closed position, at which juncture the member 60 will be rocked by the spring 55 to engage it with the end of the rib 51 to hold the cover in its closed position.

Referring to Figs. 2, 6 and 7, the upwardly-projecting lateral strips 23 and the sides of the housing 31 at the forward end of the magazine-arm 5 are formed at the top with aligned slots 68 for receiving a pair of ears or lugs 69 which project outwardly from the sides of an angular step 70. The step 70 forms a seat for a helical spring 75 acting to normally maintain the magazine-arm 5 swung downwardly with respect to the handle-member 2. The downward swinging movement of the arm 5 is limited by the engagement of the detents 37 at the sides of the housing 31, see Fig. 6, with similar detents 73 projecting inwardly from the sides of the head 3 on the member 2. As shown in Fig. 1, the detents 73 are formed by slitting the sides of the head 3 at 74 and expanding the metal inwardly at points therebelow. The upper end of the spring 75 is seated in a circular recess 76 indented into the lower face of a horizontal plate-member 77. The plate 77 fits within the head 3 of the handle-member 2 abutting the under side of a secondary plate 78 which forms a rest for a block or pad 80 of rubber bearing against the upper wall of the head 3. At its rearward end the plate 77 has a narrow lug 79 reaching outwardly through an aperture 81 at the rear of the head 3 and bent to hook over the edge thereof. At the forward end of the plate 77 its edge is beveled at 82. The secondary plate 78 has a pair of spaced lugs 83 bent downwardly over the edge of the underlying plate 77 whereof to hold the latter from moving forwardly. At the front of the head 2 is an aperture 85 through which an instrument such as a screw-driver may be inserted and twisted to pry up the forward end of the secondary plate 78 against the resiliency of the rubber pad 80. The prying upwardly of the forward end of the plate 78 will release its lugs 83 from the edge of the underlying plate 77 to allow the latter to be moved forwardly. The underlying plate 77 then may be pushed forward, that is, towards the front end of the implement to withdraw its lug 79 from the edge of the aperture 81 in the head 3 so that the parts may be

disassembled to remove the rubber pad 80 should its replacement be required. In other words, the plate 77 will be free to drop down away from the secondary plate 78 so that the latter with its rubber pad 80 may be removed from the head of the implement. The rubber pad 80 provides a cushion to absorb the shock and jar on the parts when the implement is operated to drive a fastener in the manner indicated in Fig. 3 of the drawings. The means for actuating the driver 30 are constructed and arranged as next described.

Referring to Figs. 4 and 6, the driver 30 may be constructed from a hardened metal bar of substantially rectangular shape in cross-section having a spline or key 38 projecting from its forward face. The key 38 engages through the opening or slot 36 between the edges of the inwardly-bent wings 35 at the forward end of the arm 5 with the main portion of the driver 30 slidable in the throat 27 at the rear of the wings. At the top of the driver 30 is a forwardly-projecting rectangular lug 39 spaced from the upper end of the key 38 to provide an opening therebetween. The lower end of the driver 30 is formed with a recessed face 41 which is aligned with the foremost staple S in the series in the magazine of the arm 5 for engagement with the head of the staple to drive it into the work. The staple-driver 30 is reciprocated in the throat 27 by means of its connection with the head 3 of the handle-member 2. For this purpose a hardened metal contact-member 90 is welded to the forward wall of the head 3 and provided with a pair of rectangular block-like projections 91 and 92 which straddle the lug 39 to connect the driver 30 to the member 2. The upper end of the projection 91 forms a rest for the forward end of the plate 77 as shown in Fig. 2. Referring to Fig. 3, it will be obvious that as the implement is held in the hand and its forward portion brought down against the work W the contact of the striking face 34 therewith will force the end of the arm 5 upwardly against the tension of the spring 75. During this relative movement between the arm 5 and member 2 the projection 91 on the member 90 in the head 3 will engage the upper end of the driver 30 and force the latter downwardly to drive the staple S into the work. The method of operation of the complete implement is as next explained.

The implement is loaded with fasteners by first rocking the member 60 against the tension of the spring 55 to release the end of its cross-strip 62 from the end of the rib 51 on the cover 50. The cover 50 then may be slid rearwardly as indicated in Fig. 4 and as its rearward end engages with the hook 43 on the tail 42 of the staple-pusher 40 the pusher will be retracted by and with the cover as the spring 46 is compressed. The top of the magazine thus is opened to receive the staples S and the pusher 40 withdrawn to provide for inserting them in advance of the latter. Upon manual release of the latch-member 60 its spring 55 will rock the member to engage the lower edge of its cross-strip 62 against the top of the rib 51 on the cover 50 to frictionally withhold the latter from sliding forwardly under the tension of the spring 46.

A plurality of staples S attached together in a stick or refill may be entered through the opening 67 in the top of the handle-member 2 to insert them into the magazine with the ends of their legs resting in the longitudinal grooves 10 on the interior of the arm 5. Then, by pressing the finger-lever or tab 65 on the member 60 for-

wardly to a slight extent the edge of its cross-strip 62 will be released from engagement with the top of the rib 51 on the cover 50; whereupon the spring 46 will expand to force the pusher 40 forwardly and cause its vertical wall 44 to bring up against the strip of staples placed in the magazine. The spring 46 will thus act to advance the pusher 40 to slide the staples S forwardly until the foremost staple brings up against the projections 28 forming the forward wall of the magazine. The forward movement of the pusher 40 under the expansion of the spring 46 will cause its tail 42 to slide the cover 50 forwardly to a certain extent; but the cover must be still further advanced to close the top of the magazine and this is accomplished by pressing against the finger-rests 53 at the sides of the arm 5. During this manual sliding of the cover 50 forwardly it is unnecessary to hold the latch-member 60 released as its frictional resistance to such movement is relatively slight. As the cover 50 is finally closed with its forward end in contact with the front wall-portion 25 of the magazine the latch-member 60 will be rocked by its spring 55 to engage the lower edge of its cross-strip 62 with the end of the rib 51 to maintain the cover in closed position. The forward extension 56 of the spring 55 serves to normally hold the cover down against the top of the magazine while it is being withdrawn or slid forwardly thereon; and to positively resist any upward movement of the cover when in closed relationship its forward end engages under the rearwardly-extending portions 24 of the vertical strips 23 on the arm 5 and the corresponding overlying portions of the housing 31.

After the implement is loaded in the manner explained above it is ready for manipulation to drive the staples S successively into the work. The finger-grip 4 at the end of the arm 2 is grasped in the palm and the fingers of the hand and the implement wielded in the manner of an ordinary hammer to strike the beveled face 34 at the forward end of the arm 5 against the work W. As the arm 5 is brought down into contact with the work it will be swung upwardly against the tension of the spring 75, thereby causing the upper end of the driver 39 to be engaged by the projection 91 on the contact-member 90 to force the driver down against the head of the staple and drive it into the work. As the implement is lifted away from the work the spring 75 will swing the arm 5 downwardly relatively to the member 2, thereby causing the staple-driver 39 to be slid upwardly in the throat 27 to raise its driving face 47 above the staples as shown in Fig. 2. As the staple-driver 39 is raised to this position the tension of the spring 46 will advance the staple-pushers 40 sufficiently to feed the staples S forwardly in the magazine to locate the next foremost one in the series beneath the lower edge of the driver so that the implement is prepared for another operation. It has been explained that the relative movement between the magazine-arm 5 and handle-member 2 under the tension of the spring 75 is limited by the engagement of the detents 37 and 73 shown in Fig. 6. The implement may thus be operated continuously to drive the staples progressively therefrom and into the work until the supply in the magazine is exhausted.

It has been stated that the rubber block or pad 80 in the head 3 of the handle-member 2 is provided to absorb the shock and jar on the parts of the implement. As the forward end of the

stapling-arm 5 makes contact with the work and compresses the spring 75 the rubber pad 80 will yield slightly to absorb the shock of the impact and thereby prevent crystallization of the spring 75 and the other elements of the device which would be liable to cause fracture thereof. In certain types of work the implement may be swung against relatively yieldable material, such as in tacking down carpeting or nailing fiber shingles, in which case the staple-driver 39 may penetrate into the work causing the end of the arm 5 to contact with the plate 77. When this occurs the rubber pad 80 will serve as a buffer to absorb the shock of the impact.

It will be observed from the foregoing specification that the present invention provides important improvements in the construction of the various parts of a stapling implement of the type indicated, while also facilitating and convenience the loading of its magazine with fasteners. Further, the improvement makes for more efficient operation of the implement while rendering it more economical to manufacture and proof against damage to or breakage of its parts. While the device is herein shown as embodied in a preferred form of construction, it is to be understood that modifications may be made in the form and arrangement of its parts without departing from the spirit or scope of the invention. Therefore, without limiting myself in this respect, I claim:

1. A fastener-applying implement comprising a magazine for containing a supply of fasteners, a slidable cover for closing the magazine, a pusher slidable longitudinally of the magazine to feed the fasteners forwardly therein, said cover being engageable with the pusher to retract it in the magazine, a manually operable rotary latch-member having a shoulder engageable with the end of the cover to hold it in closed position and also provided with an arcuate portion frictionally engageable with the top of the cover to maintain it in open position, and a spring for rocking said latch-member to engage it either with the end of the cover or with the top thereof.

2. A fastener-applying implement comprising a hollow magazine for containing a supply of fasteners, a slidable cover overlying the top of the magazine, a pusher slidable longitudinally of the magazine to feed the fasteners forwardly therein, a spring for advancing the pusher in the magazine, means operative by the sliding of the cover to retract the pusher in the magazine, a rotary latch-member having a detent-shoulder adapted to positively engage the end of the cover to hold it in closed position, said latch-member being formed with an arcuate portion frictionally engageable with the top of the cover to maintain it in open position, and a spring for rocking said latch-member to engage it either with the end of the cover or with the top thereof.

3. An implement of the type indicated comprising a hollow magazine for containing a supply of fasteners, a pusher slidable in the magazine for feeding the fasteners forwardly therein, a spring for advancing the pusher in the magazine, a cover slidable on the magazine for opening or closing its top, said cover provided with manually-engageable gripping means projecting at the sides of the magazine for sliding the cover, means on the pusher engageable with the cover for retracting the pusher when the cover is slid to open the magazine, and a rotatable latch-member having an arcuate portion adapted to be moved into frictional engagement with the top of

the cover to hold the latter in open position, said arcuate portion terminating in a shoulder adapted to engage the end of the cover to positively lock it in closed position.

4. In a fastener-applying implement, a hollow magazine for containing a supply of fasteners, a pusher slideable in the magazine to feed the fasteners forwardly therein, a spring for advancing the pusher in the magazine, a cover slideable along the top of the magazine and provided with finger-grips straddling its sides, means on the pusher engageable by the cover to retract the pusher in the magazine, a pivoted latch-member having an arcuate portion formed at one end to provide a finger-lever and terminating at its opposite end in a radial shoulder for engaging the end of the cover to hold it in closed position, said arcuate portion of the latch-member being adapted to frictionally engage the top of the cover to hold it in open position, and a spring for rocking the latch-member to engage it with the cover.

5. A fastener-applying implement comprising a hollow magazine for containing a supply of fasteners, a pusher slideable in the magazine for feeding the fasteners forwardly therein, a spring for advancing the pusher, a cover overlying the magazine and slideable longitudinally thereof, means on the pusher engageable by the cover for retracting the pusher when the cover is slid to open the magazine, a latch pivoted to the magazine above the cover and provided with a detent portion for engaging the cover to maintain it in closed position, and a spring for rocking the latch to engage it with the cover, said latch having manually-operable means for rocking it against the tension of the spring to release it from the cover and said latch being frictionally engageable with the cover when released from its end to maintain the cover in open position.

6. A fastener-applying implement comprising a hollow magazine for containing a supply of fasteners, a pusher slideable in the magazine for feeding the fasteners forwardly therein, a spring for advancing the pusher, a cover overlying the top of the magazine and formed with an upstanding rib extending longitudinally thereof, means

on the pusher engageable by the cover to retract said pusher when the cover is slid to open position, a latch-member pivoted on the magazine and formed with an arcuate portion with its edge engageable with the end of the rib on the cover to hold the latter in closed position, and a spring for rocking the latch-member to normally maintain the end of its arcuate portion engaged with the end of the rib on the cover to hold it closed and to also frictionally engage its arcuate portion with the top of said rib to maintain the cover in open position.

7. A fastener-applying implement comprising a hollow magazine for containing a supply of fasteners, a pusher slideable in said magazine to advance the fasteners therein, a spring for advancing the pusher in the magazine, means on the pusher engageable by the cover to retract it when the cover is slid to open the magazine, a latch-member pivoted on the magazine above the cover and formed with an arcuate portion extended radially in a finger-lever, and a helical spring concentric of the axis of the latch-member with one end anchored thereto and its opposite end extended forwardly and overlying the top of the cover, the latch-member being operative by said spring to either engage it frictionally with the top of the cover to maintain it in open position or positively with the end of the cover to hold it in closed position.
